[57] CLAIM

The ornamental design for a dental instrument table, as shown and described.

DESCRIPTION

FIG. 1 is a perspective view taken from the right side of a dental instrument table in accordance with the present invention;

FIG. 2 is a left-side view of the dental instrument table of FIG. 1, with the right-side view being a mirror image thereof;

FIG. 3 is a front elevational view of the dental instrument table of FIG. 1;

FIG. 4 is a rear elevational view of the dental instrument table of FIG. 1;

FIG. 5 is a top plan view of the dental instrument table of FIG. 1; and,

FIG. 6 is a bottom plan view of the dental instrument table of FIG. 1.
